UNITED STATES PATENT OFFICE.

ALVIN L. COX, OF ELIZABETHTOWN, KENTUCKY.

WAGON CONSTRUCTION.

1,118,531.

Specification of Letters Patent. Patented Nov. 24, 1914.

Application filed December 5, 1913. Serial No. 804,871.

To all whom it may concern:

Be it known that I, ALVIN L. Cox, a citizen of the United States, residing at Elizabethtown, in the county of Hardin and State 5 of Kentucky, have invented certain new and useful Improvements in Wagon Construction, of which the following is a specification.

My invention relates to improvements in 10 vehicles, particularly wagons, which are adapted to be propelled by an engine or drawn by draft animals, and has special reference to apparatus of the above mentioned character, embodying a track-frame 15 adapted to be moved in a novel manner, whereby a truck may be conveniently moved longitudinally thereof.

An important object of this invention is 20 to provide novel and simple means for vertically moving or adjusting the track-frame while maintaining the same substantially horizontal, whereby the truck mounted thereon to travel longitudinally thereof may be brought into horizontal alinement with a 25 car floor or the like, and means to tilt the track-frame after its proper vertical adjustment, to aid in moving the truck from the same.

A further object of the invention is to 30 provide extremely simple means for tilting the track-frame.

A further object of the invention is to improve in general the construction of such apparatuses with a view of rendering the same 35 more simple, inexpensive to manufacture, durable, and convenient in use.

Other objects and advantages of this invention will be apparent during the course of the following description.

40 In the accompanying drawings forming a part of this specification and in which like numerals are employed to designate like parts throughout the same, Figure 1 is a side elevation of apparatus embodying my invention, Fig. 2 is a plan view of the same, Fig. 3 is a fragmentary perspective view of a portion of the track-frame, Fig. 4 is a detail section through a bearing for one of the hoisting elements, and, Fig. 5 is an enlarged 45 detail section through a portion of the platform of the truck.

In the drawings, wherein for the purpose of illustration, is shown a preferred embodiment of my invention, the numeral 10 designates a lower truck-frame, embodying a rear bolster 11 and a forward bolster 12, pref-

erably rigidly connected by a longitudinal beam 13. Arranged below the bolster 11 and preferably rigidly connected therewith by any suitable means is an axle 14, upon 60 which are rotatably mounted wheels 15. Arranged below the forward bolster 12 is an axle 16, pivoted thereto at a point equidistantly between the ends thereof, and carrying at its opposite ends rotatable 65 wheels 17. The axle 16 is preferably connected with a draft appliance 18. However it is to be understood that the invention is not restricted to the use of draft appliances as the vehicle may be propelled by means of 70 an engine, as in the case of automobiles.

The numeral 19 designates an intermediate supporting frame, including transverse bolsters 20, connected by longitudinal beams 21. Arranged above the intermediate supporting frame and raised and lowered with the same by hoisting means to be described, is a track-frame 22, including longitudinal rails 23, connected at their forward ends by a transverse beam 24, and strip 25, as shown. 80 Arranged preferably upon the outer longitudinal surfaces of the longitudinal rails 23 are guide rails 26, rigidly attached thereto by any suitable means. These guide rails extend vertically upwardly beyond the longitudinal rails 23, as more clearly shown in Fig. 4.

The numeral 27 designates a guide rail attached to the beam 24, and extending transversely of the track-frame to form a 90 stop for the forward longitudinal movement of an upper movable truck, to be described.

The numeral 28 designates a vertically swinging track-frame extension, embodying longitudinal rails 29, to the outer surfaces 95 of which are attached guide rails 29', more clearly shown in Fig. 3. The adjacent ends of the rails 23 and 29, are provided with interfitting reduced extensions 30 and 31, which are pivotally connected by a transverse rod 32, passing therethrough, as shown. The reduced extension 31 is provided with a curved end 33, to engage a curved face 34 of the rail 23, preventing the farther downward movement of the rail 29, 100 such rail being preferably retained parallel with the rail 23, when occupying its lowermost position. Extending through the rear ends of the rails 23 is a transverse rod or shaft 35, with the outer ends of which are 105 connected vertically swinging latch-arms 36, provided near their outer ends with hooked

heads 37. The latch-arms 36 operate within U-shaped brackets 38, attached to the rails 29', as more clearly shown in Fig. 1. When the extension track-frame 28 is swung to its upper position, as shown in Fig. 1, it is held in such position by the latch-arms 36, and serves as a tail-gate, for preventing the movable truck from moving off of the track-frame. When the same is swung to the horizontal position, it serves as a continuation of the track-frame.

The hoisting means, above referred to, comprises preferably three screw-threaded shafts 39 and 40, which are arranged near the forward and rear ends of the lower truck-frame 10, to form a triangle. The shafts 40 are arranged near the opposite ends of the bolster 11, while the shaft 39 is arranged at a point equidistantly between the ends of the bolster 12. Each of the screw-threaded shafts 39 and 40, which are vertically arranged (see more particularly Fig. 4), operates within a screw-threaded sleeve or bearing 41, extending within an opening formed through the bolster 11 or 12, and held stationary therein by bolts 42 or the like. The extreme upper end of each of the screw-threaded hoisting shafts 39 and 40 is smooth and is rotatably mounted within a sleeve or bearing 43, mounted within an opening formed in the bolster 20, the same being rotatably held therein by any suitable means. The smooth end of each of the screw-threaded shafts 39 or 40 is provided with an annular groove 44, receiving the inner smooth end of a set screw 45, preventing the vertical movement of the intermediate supporting frame with relation to the lower truck-frame, but permitting the screw-threaded shafts 39 and 40 to be freely turned. Rigidly mounted upon the upper portions of the screw-threaded shafts 40 below and adjacent the bolster 20 are sprocket wheels 46, engaged by a sprocket chain 47, extending forwardly to engage a single sprocket wheel 48 rigidly mounted upon the screw-threaded shaft 39. The sprocket wheel 48 is rigidly mounted upon a manually operated star wheel 49 and is preferably cast integral therewith. This star wheel embodies spaced radially extending arms or spokes 50, adapted to be manually engaged by the operator. It is thus seen by turning the star wheel 49 the track frame will be raised or lowered depending upon the direction of such turning movement and retained in its horizontal position.

While I prefer to use the form of hoisting means herein shown and described, owing to the simplicity of its construction, however it is to be understood that various changes may be made in the same, if desired.

The rear bolster 20 of the intermediate supporting frame is provided at its ends with reduced cylindrical extensions 51, re-

ceiving pivot brackets 52, which are bolted or otherwise attached to the lower surface of the longitudinal rails 23, adjacent the rear ends thereof, as shown. Connected with the forward bolster 20 are upwardly extending 70 guide arms or standards 53, serving to prevent lateral displacements of the track frame 19, when the adjacent end thereof is vertically moved, as will be next explained. Preferably attached to the forward bolsters 75 20, at a point substantially equidistant between the ends thereof, is a forked bracket 54, within which is pivotally mounted, as shown at 55, a hoisting cam 56, carrying an operating lever 57. The said lever 57 80 is so arranged with respect to the star wheel 49 when the same is swung downwardly to raise the forward end of the track-frame, that it may be passed between two of the arms 50 of the star wheel, whereby it will be 85 out of the way, and if desired, the star wheel may be turned so that one arm will have clamping engagement with the lever 57 to positively prevent its improper swinging movement. However, the arm 57 is so pivot- 90 ed, when the same is swung to the vertical position, that it is moved inwardly past dead center, whereby the weight of the track-frame will securely hold it against returning movement. 95

The numeral 58 designates a platform included in a longitudinally movable upper truck, supported by rollers 59, adapted to travel upon the rails 23 and 29. While I have found that satisfactory results are obtainable by using the rollers 59 it is to be understood that I may also use bearing-balls or other anti-friction means, and that in some instances the anti-friction means may be entirely dispensed with. I also prefer to 100 arrange rollers 60 between the longitudinal edges of the platform 58 and the guide rails 26, to prevent undue friction between the upper truck and these guide rails. Outwardly extending handles 61 are rigidly attached to the platform 58, by means of which the platform may be moved longitudinally. 110

In the use of the apparatus, when the same is being loaded, the extension track-frame 28 is swung to the horizontal position, its outer end preferably extending into a car door or the like to be supported thereby. The track-frame may be raised or lowered to assume the proper vertical position with respect to the car door, by turning the star wheel 49, as is obvious. The upper movable truck including the platform 58 is then moved longitudinally upon the track-frame, after which the frame extension 28 is swung to the upper position, as shown in Fig. 1. When unloading, the track-frame 28 is again swung to its lower position, with its outer end extending into a car door or the like for engaging the door of the car to be supported 130

thereby. The track-frame may be raised or lowered to assume the desired vertical position. This having been done, the lever 57 is swung downwardly, for raising the forward 5 end of the track-frame, whereby the upper track may be moved longitudinally of the same with the least effort. It is obvious that instead of arranging the cam 56 at the forward end of the track-frame, the same may 10 be arranged at one side of the same, whereby the track-frame may be tilted transversely instead of longitudinally, the track-frame and upper track being suitably altered whereby this construction could be advantageously 15 employed.

It is to be understood that the form of my invention herewith shown and described is to be taken as a preferred example of the same, and that various changes in the shape, 20 size and arrangement of parts may be resorted to without departing from the spirit of the invention or the scope of the subjoined claims.

Having described my invention, I claim:—
25 1. The combination with a wheeled frame, of an intermediate frame arranged above the same, hoisting mechanism arranged between the frames and including a manually operated wheel arranged near the forward end 30 of the frames and having relatively long radially extending spaced arms, an uppermost frame movably mounted upon the intermediate frame, a cam connected with the intermediate frame to turn thereon and engage the uppermost frame to raise and 35 lower the same, and an operating lever se-

cured to the cam and adapted to be swung downwardly to occupy a position between the arms of the manually operated wheel to lock the wheel against rotation.

2. The combination with a wheeled frame, of an intermediate frame including forward and rear bolsters, a plurality of hoisting mechanisms interposed between the rear bolster and the wheeled frame, a single hoist- 45 ing mechanism interposed between the forward bolster and the wheeled frame, sprocket wheels connected with the hoisting mechanisms to operate the same, a sprocket chain engaging the sprocket wheels, a man- 50 ually operated wheel connected with the forward sprocket wheel and including relatively long radially extending arms, a forwardly extending bracket connected with the forward bolster, a cam connected with the free end of the bracket to raise and lower an uppermost frame, a lever connect- 55 ed with the cam and adapted to be swung downwardly and inwardly to assume a position past the dead center of the pivoted cam and between two of the arms of the wheel whereby the cam and wheel are both locked against turning movement, and an uppermost frame arranged upon the intermediate 60 frame and engaging the cam.

In testimony whereof I affix my signature in presence of two witnesses.

ALVIN L. COX.
